W. F. KOKEN,
CHILD'S HAIR CUTTING CHAIR,
APPLICATION FILED SEPT. 19, 1919.

1,334,038.

Patented Mar. 16, 1920.

UNITED STATES PATENT OFFICE.

WALTER F. KOKEN, OF ST. LOUIS, MISSOURI.

CHILD'S HAIR-CUTTING CHAIR.

1,334,038.

Specification of Letters Patent. Patented Mar. 16, 1920.

Application filed September 19, 1919. Serial No. 324,804.

To all whom it may concern:

Be it known that I, WALTER F. KOKEN, a citizen of the United States, residing at St. Louis, Missouri, have invented a certain 5 new and useful Improvement in Children's Hair-Cutting Chairs, of which the following is a full, clear, and exact description, such as will enable others skilled in the art to which it appertains to make and use the 10 same.

This invention relates to chairs of the kind that are used by barbers, dentists and other specialists for supporting a person on whom work is being done.

15 The main object of my invention is to provide a barber's chair or dentist's chair which will be so attractive to a child that it will not be necessary to coax or offer inducements to the average child to get the 20 child to sit in the chair.

Another object is to provide a child's chair that has the characteristics above mentioned and which is so constructed that the portion of the chair on which the child 25 sits can be raised and lowered and also revolved so as to facilitate the work of the person operating on the child.

To this end I have devised a chair that comprises a base portion, a vertically-adjustable support or stem carried by said base portion and a toy animal mounted on said stem so as to form a seat for the child occupying the chair. The animal on which the child sits is mounted on the vertically-adjustable stem in such a manner that it can be moved so as to give the impression of an animal in motion, and in the preferred form of my invention, as herein illustrated, the mechanism that is employed for raising and 40 lowering the stem is combined with the toy animal on which the child sits in such a manner that the operation of rocking or moving said animal effects the operation of the mechanism that raises and lowers said 45 stem.

Figure 1 of the drawings is a side elevational view, partly in vertical section, of a child's hair cutting chair constructed in accordance with my invention; and

50 Fig. 2 is an enlarged vertical sectional view of the upper portion of the stem, illustrating the rockable plate thereon and the means for holding said plate stationary.

55 Referring to the drawings which illustrate the preferred form of my invention, A designates the base portion of the chair

and B designates a vertically-adjustable support or stem mounted on said base portion and provided with a toy animal C that forms the seat for the occupant of the chair. 60 I have herein illustrated the chair provided with a hobbyhorse C that is mounted on the stem B in such a manner that said horse can be rocked in the same manner as an ordinary hobbyhorse, but I wish it to be understood that my broad idea is not limited to 65 a chair provided with a hobbyhorse, as it is immaterial, so far as my invention is concerned, what particular type or kind of animal is used to form the seat of the chair or 70 how said animal is mounted on the stem, so long as it can be moved relatively to the stem to give the impression of an animal in motion.

In the form of my invention herein illustrated the animal C that constitutes the seat of the chair is carried by a plate 1 provided with a depending portion 2 that is pivotally connected at 3 to the upper end portion of the stem B, thereby enabling said animal 80 with its rider to be rocked upwardly and downwardly, as indicated in broken lines in Fig. 2 in the same manner that an ordinary hobbyhorse operates. Normally, the horse C is held at rest or is prevented from rocking by means of a locking device 4 consisting of a wedge-shaped block that is interposed between a bearing surface 4^a on the underside of the plate 1 and a bearing surface 4^b on the upper end of the stem B. Said locking 85 device is preferably connected to the inner end of an operating rod 5 that leads forwardly under the body of the horse and which is reciprocatingly mounted in a bearing 6 on the underside of the plate 1. The 90 rod 5 is provided with a cross pin 7 that fits in notches 6^a in the bearing 6 when the locking device 4 is in its operative position, and a spring 8 is mounted on the rod 5 between the bearing 6 and the locking device 100 4 so as to exert pressure on said locking device in a direction tending to hold it in engagement with the co-operating bearing surfaces on the plate 1 and standard B.

When it is desired to rock the horse C the 105 person in charge of the chair pulls the rod 5 forwardly so as to disengage the locking device 4 from the plate 1 and stem B and then gives said operating rod a quarter turn 110 so as to arrange the pin 7 in said rod vertically and in engagement with the front end of the bearing 6, thus holding the locking

device 4 retracted or in its inoperative position. Thereafter, the horse C can be rocked upwardly and downwardly. A yielding stop or spring-pressed buffer 8 is preferably mounted in a lug 9 on the front side of the stem B so as to form a yielding abutment against which the locking device 4 strikes when the horse is rocked.

Any suitable means can be used for raising and lowering the stem B of the chair and for locking said stem in adjusted position. In the form of my invention herein illustrated the stem B is raised, lowered and locked in adjusted position by a hydraulic mechanism of the kind used in Koken barbers' chairs and comprising a stationary socket member D in which the stem B slides and a hollow pump plunger 10 reciprocatingly mounted inside of the stem D for forcing a liquid from said stem into the space between the bottom of the socket member D and the closed lower end portion of the stem, the stem B being provided in its end wall with a valve 11 that opens automatically on the downward stroke of the pump plunger 10 and said plunger being provided with a valve 12 that opens on the upward stroke of said plunger and thus permits liquid to enter the space between the under side of said plunger and the end wall of the stem B, it being understood that the stem B is hollow and filled with oil or other suitable liquid. A clamping device 13 that is arranged in an opening in the side wall of the stem B is adapted to be forced downwardly into snug engagement with the side wall of the socket member D by an inclined surface on the plunger 10 when said plunger is moved upwardly a certain distance. I make no claim to the particular type or construction of the hydraulic mechanism above described for raising and lowering the stem of the chair, as said mechanism has long been in use and is of the general construction shown in expired U. S. Patent No. 548,258 to E. E. Koken, dated October 22, 1895. In my present chair, however, the device 14 that actuates the pump plunger 10 is pivotally connected at its upper end to a crank arm or bell crank lever 15 on the depending portion 2 of the plate 1 that carries the toy animal C, so as to enable the plunger 10 to be actuated by rocking the animal on which the child sits. This feature adds greatly to the novelty of the chair, as the stem B moves vertically when the animal C rocks and thus gives the child the impression that it is due to his efforts that the seat of the chair is raised or lowered. In the actual operation of the chair the person in charge of the chair grasps the head of the animal C and limits the degree said animal rocks up and down, as it is necessary that the plunger 10 be moved less than its full stroke during the operation of raising the stem of the chair.

After the stem has been raised to the required height the person in charge of the chair moves the locking member 4 into engagement with the cooperating surfaces 4^a and 4^b on the plate 1 and on the upper end 70 of the stem B of the chair so as to force the rear end portion of the plate downwardly into engagement with an inclined surface 4^c on the stem, thereby locking the operating mechanism for the stem and also holding 75 the animal C at rest, or, in other words, in such a manner that it can be neither rocked nor revolved.

The animal C is equipped with a saddle 16 on which the child sits, and if desired, said saddle can be provided with a rear portion or back 17 that is removably mounted so as to facilitate arranging the child in operative position on the saddle, the back portion 17 of the saddle of the chair herein illustrated 85 being provided with dowel pins 17^a that fit in openings in the seat portion of the saddle.

Having thus described my invention, what I claim as new and desire to secure by Letters Patent, is:

1. A chair of the type referred to, comprising a vertically-adjustable support, a toy animal mounted on said support in such a manner that it can be moved relatively to said support to give the impression of an animal in motion, and means for causing said support to move vertically when said animal moves.

2. A chair of the type referred to, comprising a vertically-adjustable support, 100 mechanism for raising and lowering said support, a toy animal rockably mounted on said support, and means operated by said animal for actuating the mechanism that raises and lowers the support.

3. A chair of the type referred to, comprising a base, a vertically-adjustable support mounted on said base, a toy animal rockably mounted on said support, mechanism for raising and lowering said support, 110 and means operated by the movement of said animal for actuating said raising and lowering mechanism.

4. A chair of the type referred to, comprising a base provided with a socket member, a stem reciprocatingly mounted in said socket member, a hydraulic mechanism for raising and lowering said stem, a toy animal rockably mounted on said stem to form a seat for the occupant of the chair, and an 115 actuating device for said hydraulic mechanism operated by the movement of said animal.

5. A chair of the type referred to, comprising a vertically-adjustable stem, a toy 125 animal rockably mounted on said stem to form a seat for the occupant of the chair, mechanism for raising and lowering the stem and for locking the stem in adjusted position, and means operated by the move- 130

ment of said animal for actuating said mechanism.

6. A chair of the type referred to, comprising a vertically-adjustable stem, a toy animal rockably mounted on said stem to form a seat for the occupant of the chair, mechanism adapted to be operated by the movement of said animal for raising and lowering the stem, and means under control 10 of the operator in charge of the chair for preventing said animal from being rocked.

7. A chair of the type referred to, comprising a vertically-adjustable stem, a raising and lowering mechanism for said stem 15 comprising a pump plunger, a rockable member on said stem provided with a lever that is connected to said pump plunger so as to actuate said plunger when said member rocks, and a child's toy mounted on said 20 rockable member to form a seat for the occupant of the chair.

8. A chair of the type referred to, comprising a vertically-adjustable stem, a toy animal rockably mounted on said stem to 25 form a seat for the occupant of the chair, a wedge-shaped locking device that is adapted to be interposed between said animal and stem to hold the animal at rest, and means for holding said locking device in an inoperative position when it is desired to rock 30 said animal.

9. A chair of the type referred to, comprising a vertically-adjustable stem, a rockable member at the upper end of said stem 35 provided with a depending portion that is pivotally mounted on said stem, a toy animal on said rockable member that forms a seat for the occupant of the chair, a crank arm or lever on the depending portion of 40 said rockable member, a mechanism for raising and lowering said stem operatively connected to said crank arm, a wedge-shaped locking device adapted to be interposed between said rockable member and the upper 45 end of said stem to hold said rockable member at rest, and an operating rod for said locking device journaled in a bearing on said rockable member and leading forwardly to the front of said animal.

50 10. A chair of the type referred to, comprising a vertically-adjustable stem, a rockable member at the upper end of said stem provided with a depending portion that is

pivotsly mounted on said stem, a toy animal on said rockable member that forms a 55 seat for the occupant of the chair, a crank arm or lever on the depending portion of said rockable member, a mechanism for raising and lowering said stem operatively connected to said crank arm, a wedge-shaped 60 locking device adapted to be interposed between said rockable member and the upper end of said stem to hold said rockable member at rest, an operating rod for said locking device journaled in a bearing on said rockable member and leading forwardly to the front of said animal, a spring arranged on 65 said operating rod between said locking device and the bearing in which said rod is journaled, a cross pin in said rod that is adapted to enter a notch in said bearing when said locking device is in its operative position, and a yielding buffer on said stem for limiting the downward movement of said animal when it is being rocked. 75

11. A chair of the type described, comprising a support, a toy animal rockably mounted on said support to form a seat for the occupant of the chair, a surface on said support arranged at one side of the axis of 80 movement of said animal for limiting the rocking movement of same in one direction, and a movable device arranged at the other side of the axis of movement of said animal for holding it at rest. 85

12. A chair of the type referred to, comprising a base, a vertically-adjustable stem, mechanism for raising and lowering said stem, a rockable member on said stem adapted to carry a toy animal that serves 90 as a seat for the occupant of the chair, and a connection between said rockable member and the mechanism that raises and lowers the stem of the chair.

13. A chair of the type referred to, comprising a base, a vertically-adjustable stem carried by said base, mechanism for operating said stem, a rockable member on said stem adapted to carry a device which serves as a seat for the occupant of the chair, means 100 controlled by said rockable member for actuating said stem operating mechanism, and means for preventing said rockable member from moving relatively to the stem of the chair. 95

WALTER F. KOKEN.
